UNITED STATES PATENT OFFICE.

FRANK B. MANVILLE AND CHARLES S. WEEKS, OF WATERBURY, CONNECTICUT, ASSIGNORS TO THE BROCKNER EVANS BALE TIE COMPANY, OF ST. LOUIS, MISSOURI.

MACHINE FOR MAKING BALE-TIES.

SPECIFICATION forming part of Letters Patent No. 617,253, dated January 3, 1899.

Application filed March 4, 1898. Serial No. 672,577. (No model.)

To all whom it may concern:

Be it known that we, FRANK B. MANVILLE and CHARLES S. WEEKS, citizens of the United States, residing at Waterbury, county of New Haven, State of Connecticut, have invented 5 a new and useful Machine for Making Bale-Ties, of which the following is a specification.

This invention relates to machines for making metallic ties for use in baling hay, cotton, 10 or other analogous substances; and our object is to produce a machine which will automatically sever wire into lengths, then bend one end of each length to form a loop, then twist the lapping portions to leave an eye, 15 and finally deposit the finished ties in a receptacle, means being also provided for giving a signal when a predetermined number of ties have been so deposited, and provisions being also made for adjusting the feed of the 20 wire to produce ties of the desired length.

Further objects of our invention are to produce a machine of this type which is simple in construction, in view of the several manipulations and transfers of the lengths of wire, 25 and which machine is capable of producing the finished ties at a high rate of speed.

To these ends our invention consists in the construction and combination of parts, substantially as hereinafter described and 30 claimed.

In the accompanying drawings, Figure 1 represents a plan view of a machine embodying our invention. Fig. 2 represents a side elevation of the same and showing also a wire-straightener. Fig. 3 represents an elevation from the side opposite that shown in Fig. 2. Fig. 4 represents a detail elevation of the 35 means for adjusting the length of reciprocations of the rack-bar. Fig. 5 represents an edge view of the parts shown in Fig. 4. Fig. 40 6 represents an enlarged detail section of the feeding-disks and their bearings, said figure being drawn on the line 6 6 of Fig. 7 and looking in the direction of the arrow crossing said line. Fig. 7 represents a section on line 7 7 of Fig. 6 and looking in the direction of the 45 arrow crossing said line. Fig. 8 represents a detail elevation of the friction strap or yoke for preventing backward rotation of the feed- 50 ing-disks and for holding the disks together

to cause them to "bite" upon the wire. Fig. 9 represents a detail plan of the cutting-off mechanism. Fig. 10 represents a section on the line 10 10 of Fig. 9, looking in the direction of the arrow crossing said line. Fig. 11 55 represents an enlarged detail plan view of the twisting mechanism. Fig. 12 represents a side elevation and part section of the same. Fig. 13 represents a detail elevation of a portion of the twister-shaft and the sliding sleeve 60 thereon as viewed from the side opposite that indicated in Fig. 12. Fig. 14 represents a section on line 14 14 of Fig. 11, looking in the direction of the arrow crossing said line. Figs. 15, 16, and 17 are detail elevations of the 65 operating end of the twisting-shaft and showing the bender in different positions. Fig. 18 represents a section on line 18 18 of Fig. 15. Fig. 19 represents a detail elevation of the mechanism for operating the carrier or 70 reel. Fig. 20 represents a view from the right of Fig. 19. Fig. 21 represents a plan view of the parts shown in Figs. 19 and 20. Fig. 22 represents an enlarged detail elevation of the end of one of the arms of the rotary carrier 75 or reel. Fig. 23 represents a view from the right of Fig. 22. Fig. 24 represents a detail elevation of the temporary holder for the lengths of wire after they are severed. Fig. 25 represents a section on line 25 25 of Fig. 80 80 24, looking in the direction of the arrow crossing said line. Fig. 26 is a view similar to Fig. 24, enlarged therefrom and showing the parts in a different position. Fig. 27 represents an enlarged detail elevation of the rotary car- 85 rier or reel and the holder from which the carrier takes the lengths. Fig. 28 is a view similar to Fig. 27, but reduced therefrom and showing more of the adjacent features of construction. Fig. 29 represents an elevation 90 from the right of Fig. 28, parts being in section on the line 29 29 of Fig. 28. Figs. 30 and 31 represent enlarged detail views, partly in section, of the means for signaling the finishing of a particular number of the bale- 95 ties, the bearing for the worm-shaft being omitted from Fig. 30.

Similar reference characters indicate the same parts throughout the several views.

The bed-plate of the machine is indicated 100

at 1, supported by legs 2 and having suitable bearings for the main shaft 3 and counter-shaft 4, the former having a pulley 5 for a driving-belt (not shown) and the latter having the cams, hereinafter described, secured thereto. At one end of the shaft 4 is a gear 8, meshing with and driven by a pinion 9 on the main shaft. At the other end of the counter-shaft or cam-shaft 4 is a gear 11, (see Figs. 1, 3, 4, and 5,) which meshes with a gear 12 on a short shaft 13, mounted in a bracket 15, (see Fig. 5,) that is suitably secured to the frame of the machine. Both of the shafts 3 and 4 also have their bearings in this bracket 15 and also in another bracket 16, (see Figs. 1 and 2,) secured to the frame or bed of the machine, at the front side thereof, as viewed in Fig. 2.

Secured to the end of the shaft 13 and adjacent to the gear 12 is a disk 17, having a dovetail groove 19 formed diametrically across its face, in which groove a block 20 (see dotted lines in Fig. 4) is fitted and adapted to be moved radially by means of a threaded rod 21, which passes through a similarly-threaded hole in said block in a well-known manner. Near the outer end of the rod 21 are fixed collars 22, between which is a block 23, secured in the groove 19. The end of the rod has a squared socket, whereby a wrench or key is employed to rotate the rod and adjust the block 20 toward and from the center of the disk 17. The said block 20 carries a wrist-pin 24, which enters a slot 26 in a lever 27, the latter being pivoted to the frame, as at 28. As will now be understood, the throw or extent of movement of the lever 27 may be adjusted by means of the threaded rod 21, and since this lever operates the feed, as presently described, the adjustment of the block 20 and its wrist-pin 24 by means of said rod 21 effects the desired adjustment of the feed of the wire.

The feed-disks 30, between the grooved peripheries of which the wire is gripped and by the rotation of which the wire is drawn from a suitable coil or other source of supply, (not shown,) are represented in Figs. 1, 2, and 3, and their operating mechanism is shown more in detail in Figs. 6, 7, and 8. A standard 31, rising from the bed-plate 1 and forming part of the frame of the machine, is provided with two offsets 32, (see Figs. 3 and 6,) which are provided with dovetail grooves in line with each other to form ways for a slide 33, the upper and lower edges of which are toothed to form a rack. This slide-rack is connected with the upper end of the lever 27 by a pitman or connecting-rod 34, whereby movements of said lever reciprocate the slide-rack to a greater or less extent, according to the adjustment of the wrist-pin above described.

In the standard 31 are bearings for the sleeves or tubular shafts 35, one end of each of said shafts having secured thereto or integral therewith a pinion 36, which meshes

with one of the compound pinions 47, presently described, and the other end having a ratchet-toothed disk 37. (See Figs. 6 and 7.) Each sleeve or shaft 35 receives or forms a bearing for a shaft 38, on the outer end of which is mounted one of the feed-disks 30, having a pawl 39 in engagement with the ratchet 37. The hubs of the feed-disks are somewhat extended to form bearing-surfaces 40 for friction-pads 41, of any suitable material, said pads being held in position by a yoke or strap 42, (see Fig. 8,) the upper ends of which are threaded and passed through a cap 43 and are provided with nuts 44, by means of which the two friction-pads may be adjusted to bear with more or less pressure on the surfaces 40.

As shown in Fig. 6, one side of the standard 31 is provided with threaded sockets 45. These are to receive studs 46, (see Fig. 3,) on which are freely mounted compound pinions 47, the larger of which mesh with the pinions 36 and the smaller of which mesh with the two racks formed on the reciprocating slide 33.

It will now be understood that the reciprocations of the slide-rack 33 cause the ratchets 37 to have a reciprocating rotary motion through the medium of the tubular shafts 35 and the pinions 36 and idler-pinions 47, and that when this motion is in one direction the disks will be caused to rotate in the direction of the arrows thereon in Figs. 3 and 7, owing to the engagement of the pawls with the ratchets, and that on the return movement of the reciprocating parts the ratchets move freely under the pawls, while the disks are prevented from retrograding by the friction-pad mechanism above described. The diameters of the feed-disks are such and the compound pinions 47 are so proportioned for multiplying speed that with a somewhat limited throw of the lever 27 we are enabled to obtain a wire-feed of any desired length, according to the dimensions and the throw adjustment of the lever.

The wire is passed directly between the feed-disks and is preferably drawn through a wire-straightening mechanism, (indicated at 48 in Fig. 2 in a conventional manner.) This mechanism may be of any preferred form, and we do not illustrate it in detail, it being sufficient for the purposes of this specification to state that it is mounted on a standard 50 and is of a type that is rotated about the wire as it is drawn along by means of a power-driven belt 49.

A fixed guide 51 (see Figs. 2, 9, and 10) is provided with a tapered end to enter the space between the feed-disks at the discharge side of their contacting points and has its internal longitudinal bore or passage of a size to receive the wire as it leaves the feed-disks. This guide is secured in an ear 52, projecting from a plate 53, by means of a set-screw 54, and said plate is adjustably secured on a portion of the standard 31 by means of a screw

55 passing through a slot 56 in said plate. The rear end of the guide is preferably somewhat rounded, and with this a cutter 57 cooperates to sever the wire after each feed 5 movement has ceased. The cutter is adjustably secured to a slide 58 by means of a screw 59 passing through a slot 60 in the cutter-shank, and said slide is fitted to a groove or way formed in the plate 53 at a right angle to 10 the guide 51. A spring 61 is confined between a portion of the plate 53 and an angular offset 62 of the slide 58 and tends to hold the slide and cutter in inoperative positions and to return them after the wire has been severed, as will now be described.

15 A lug or shoulder 63, rising from the cutter-slide, is operated against by one end of a lever 64, (see Fig. 1,) which passes through an opening 65 in the standard 31 (see Fig. 6) 20 and is fulcrumed in said opening by a pin, as indicated by the dotted circle 66 in Fig. 1. The other end of the lever 64 carries a pin or roll 67, which is operated against by a cam 68 on the end of a drum 69, mounted on shaft 25 4. This cam operates quickly and at a time after the feed or advance of the wire has ceased.

30 Referring to Fig. 3, it will be seen that at some distance from the main frame of the machine is a leg or standard 70. This, in connection with parts of the main frame, supports the parts which temporarily hold the severed blanks or lengths of wire and also carries the outer bearing for the shaft of the 35 rotary carrier or transferrer, hereinafter described.

The upper end of the standard 70 is connected with a standard 71, rising from the bed-plate 1, by means of a rod 72, which supports the temporary receiver or table for the blanks. We have illustrated but one standard 70; but it is to be understood that more may be employed and that the receiver or table may be of any length to accommodate 45 the greatest length of blanks desired. As shown in the drawings, the receiver is in two sections to permit the ends of one set of arms of the transferrer to pass between the sections, the other set of arms being beyond the end 50 of the receiver, (see Fig. 3;) but when more sets of transferrer-arms are employed there will be added standards 70 and sections of receivers. The two sections of receivers illustrated are supported from the rod 72 by means 55 of hangers 73, (see Figs. 1, 2, and 3,) and each section consists of a base portion or table 74, to which is hinged, by means of suitable ears, a cover 75, having a groove 76 in its lower face, (see Figs. 24, 25, 26, and 27,) the two 60 sections of covers being connected by a bridge or strip 77, as shown in Figs. 1, 2, and 3.

The groove 76 is in line with the exit end of the orifice for the wire in the guide 51 and receives the wire before it is severed by the 65 cutter and holds it while being cut off. In order to release the blank from the groove, so that it may be taken by the fingers at the

ends of the arms of the transferrer, (not yet described,) it is necessary to raise the cover on its hinges. In Figs. 24 to 27 we illustrate 70 a single arm 78, extending back of the hinged edge of the cover; but it is to be understood that in practice there may be a number of such arms 78, each having means to depress it to raise the frontedge of the cover, as shown 75 in Figs. 26 and 27.

The arm 78 is depressed at the proper time by means of an elbow-lever 79, pivoted at 80 to one of the hangers 73 and having its longer or horizontal arm extending over the arm 78. 80 The upper arm of the elbow-lever is connected by a link 81 with another elbow-lever 82, pivoted at 83 to another hanger 73. The lever 82 is connected by a link 84 with an arm 85 of a rock-shaft 86, (see Figs. 24 and 26 in 85 connection with Figs. 1, 2, and 3,) mounted in a bearing at the upper end of a standard 87, rising from the bed-plate of the machine. Another arm 88 of the rock-shaft is provided with a pin 89 and has attached to it one end 90 of a spring 90, the other end of the spring being connected at 91 to the bed-plate of the machine. (See Figs. 24 and 26 in connection with Fig. 3.) The parts are normally held in the positions shown in Figs. 3, 24, and 25 by 95 the tension of spring 90, thus permitting the cover 75 to remain closed. To raise the arm 88 and through the connections described cause the elbow-lever 79 to depress the arm 78 and raise the cover, we provide a yielding 100 finger 92, pivoted to the slide 33 at 93. (See Fig. 3.) The finger carries a pin 94 on one side, and back of the finger a pin 95 projects from the slide and acts as a back-stop to prevent the finger from moving in that direction. 105 A spring 96 connects the pins 94 and 95 and serves to normally hold the finger against the back-stop. During the backward movement of the slide-rack 33 the spring 96 yields and permits the pivoted finger 92 to pass under 110 the arm 88 without disturbing the latter; but on the forward movement of the slide-rack the finger is held upright by the back-stop 95, and consequently the upper end of the finger slides along the under side of the arm 115 88 and lifts it, and thus through the connections described raises the cover 75. The cover 75 is held in raised position all the time the finger 92 is passing along the straight under side of the arm 88 toward the end of 120 the latter, thus giving the transferrer-arm 125 123, which is hereinafter described, time to carry a wire blank out from under the cover 75.

It is to be borne in mind that the forward movement of the slide-rack just described 130 does not feed the wire, said feed taking place only when the rack is moving to the left from the position shown in Fig. 3. Therefore the cover 75 is lifted to release the wire after the feed has ceased and after the requisite length has been cut off and just before the next feed movement of the disks.

As hereinbefore stated, there are two or more sets of arms in the mechanism for tak-

ing the blanks from the temporary receiver just described. In the drawings there are two of such sets illustrated, the ends of the arms of one set passing between the adjacent 5 ends of two sections of the receiver. During each feed of the wire these arms are stationary and the wire is fed through openings in the ends of the arms which are at that time in alinement with the guide 51 and with the 10 groove 76 of the temporary receiver. We will now describe the construction and operation of this mechanism which takes the blanks from said receiver and transfers them 15 first to the twisting mechanism and then to the final receiver.

In connection with Figs. 1, 2, and 3 reference is to be had to Figs. 19, 20, 21, 22, 23, and 27. The shaft 97 of the rotary transerrer is mounted in suitable bearings 98 and 99, 20 supported, respectively, by the standards 70 and 71, and said bearings are vertically adjustable in order to insure that the openings in the ends of the arms may be brought into exact alinement with the groove 76 of the 25 temporary receiver. The means by which this adjustment may be effected are illustrated in Fig. 19, in which the bearing-sleeve 99 is shown as provided with two sockets 100 to receive the ends of screws 101, tapped through 30 suitable openings in portions of the standard 71 and provided with set-nuts 102. The inner end of the shaft 97 extends through the bearing-sleeve 99 and has secured thereto a disk 103, provided with four equidistant 35 notches 104, each of which has a radial side and a tangential side, (see Fig. 20 in connection with Fig. 19,) and secured adjacent to or forming a part of the disk 103 is a collar or flange 105, which also has four equidistant 40 notches, as at 106, these latter, however, having sides which are substantially parallel, but flaring somewhat at their mouths, as indicated by dotted lines in Fig. 20. A bolt 107 is adapted to enter any one of the notches 106 45 to hold and lock the flange 105, disk 103, and the shaft 97 and its arms in proper position for the alinement of the openings in the ends of said arms above mentioned and to be presently described in detail. This bolt 107 is 50 mounted to slide in a horizontal groove or way formed in a block 108, that is fixed to a portion of the frame of the machine, and the said bolt is normally held in one of the notches 106 by a spring 109, coiled about a pin 110 in the side of the block and having one end secured, as at 111, and the other end pressing against the outer side of a pin 112, projecting from the side of the bolt.

Loosely pivoted on the end of the shaft 97 60 is a lever 113, having one end formed as a cam-surface 114, which is adapted to engage the inner side of the pin 112 of bolt 107 and force the bolt out of the notch in the flange 105 against the action of spring 109, and thus 65 release the transerrer. The other end of the lever 113 is provided with a pawl 115, which is kept in engagement with the periphery

of the disk 103 by a suitable spring. (Not shown.) When the lever 113 is moved one-fourth of a rotation to the right from the position shown in Fig. 20, the pawl 115 enters the notch 104 at the right just as the cam 114 engages the pin 112 of the bolt and causes the release of the transerrer, so that on the return movement of the lever to the position shown in Fig. 20 the disk 103 and the entire transerrer is given a one-fourth revolution. These oscillating movements of the lever are imparted by means of a lever 116, pivoted at 75 117 (see Figs. 2 and 3) to a bracket on the 80 underside of the bed-plate and having at one end a roll 118, riding on a cam 119, carried by shaft 4. A spring, as at 120, keeps the roll in engagement with said cam, and the other end of the lever 116 is connected with 85 the lever 113 by a link 121, adjustably jointed, as at 122, in order to secure exactness in the throw of the lever 113.

The means for intermittently rotating the transerrer having thus been explained, we 90 will now describe the construction of the details thereof, referring particularly to Figs. 21, 22, 23, 27, 28, and 29 in connection with Figs. 1, 2, and 3.

The shaft 97 is provided with a plurality 95 of sets of arms, each set consisting of four arms 123 equidistant from each other. As the sets of arms are duplicates of each other, description of one set and of the means for retaining the blanks in their openings and 100 for discharging them therefrom will be sufficient for all. In the end of each arm 123 is an open slot or recess 124, which is normally closed by a latch or hook 125, formed on the outer end of a lever 126, pivoted to the arm 105 at 127 and having a pin 128 projecting from its other end. A spring 129 is coiled about the pivot-pin and has one end connected to the pin 128 and the other end connected to the stud 130, projecting from the arm 123. The 110 spring has a tendency to hold the lever in engagement with the stud 130, with the hook 125 overlapping the recess 124, so as to form a substantially circular opening for the wire. On the side of each arm opposite that to which 115 the lever is pivoted is a stud 131, having a recess corresponding with the recess 124 and provided with a conical entrance-mouth (see dotted lines in Fig. 23) to guide the end of the wire as it approaches the arm 123. As 120 each arm reaches its lowermost position the hook is opened to permit the wire to be dropped out by means of a stop or lug 132, (see Figs. 28 and 29,) carried by an arm 133, adjustably supported in a slideway formed 125 in a bracket 134, carried by a suitable part of the frame. This lug 132 is arranged in the path of movement of the end of the lever 126, so that when said lever 126 contacts with the lug 132 it will first cause the hook to open the 130 recess in the arm 123 to release the wire or bale-tie, and then pass by the lug, so that the spring 129 will cause the hook to close the recess again.

Before the operation of releasing the tie, as just described, takes place the wire blank has had one end doubled and twisted while held by the arms 123 in a stationary position 5 half-way between the positions of receiving and discharging, and we will now describe the mechanism for performing this operation. Referring to Figs. 1, 2, and 11 to 18, inclusive, the shaft of the twister is indicated at 135, mounted in a bearing formed in a block 136 on the bed-plate 1, the cap-piece of the bearing being indicated at 137. The rear end 10 of said shaft is provided with a pinion 138, which meshes with and is driven by a gear 139 on a short shaft which is mounted in a bearing in a block 140 and has a smaller gear or pinion 141 at its other end. The pinion 141 meshes with and is driven by a rack 142, fitted to slide in a suitable guide or way 15 (not shown) in the side face of the block 140 and having a stud provided with a roll 143, which enters a cam-groove 144 in the drum or cylinder 69 on shaft 4. Each rotation of the shaft 4 and its cam-cylinder imparts to 20 the slide-rack a complete forward-and-back movement, and this through the multiplying-gearing 138, 139, and 140, above described, rotates the shaft 135 several times in one direction (about three as now geared) and then 25 returns the shaft. The cam-groove 144, however, is formed so as to permit a dwell in the movements of the shaft at the end of each series of rotations in one direction, for a purpose presently explained. The other end of 30 the shaft 135 is divided so as to form a recess 145 to receive one end of the wire blank x as it is passed thereto by the arms of the trans- 35 ferrer at the end of the first quarter-revolution of said transerrer. The ends of the two arms 146 each side of the recess 145 are 40 provided with openings in line with each other to receive a pin 147, the inner end of which is beveled, as at 148 in Fig. 18, to prevent the end of said pin from catching on the 45 wire when the pin is moved inward, and the outer end of said pin 147 is connected to a lever 149, pivoted to an ear 150 on the outer side of one of the arms 146. The lever 149 is 50 provided with a pin 151, on which a spring 152 bears to hold the lever normally in the 55 position shown by full lines in Fig. 11, with the pin 147 withdrawn from across the recess 145.

Two lugs 153 depend from the lower edges 60 of the arms 146 and support a pin 154, which in turn supports and guides the bending-finger 155. This bending-finger is of peculiar construction, its outer portion or tip 156 extending upward in an inclined direction and 65 then curving forward and downward and having a groove 157 formed in its upper edge, which groove continues over and under the end, as clearly shown by the full lines in Fig. 11 and by dotted lines in Figs. 15, 16, and 17.

70 The intermediate portion of the bending-finger is provided with a slot 158, that is curved in a direction substantially the reverse of

the curvature of the tip 156, and this slot receives and serves to guide the finger on the pin 154, so that when a wire has been lowered by the transerrer to the position indicated by full lines in Fig. 12 and the lever 149 has been operated by the means presently described to move the pin 147 across the recess 145 and the finger 155 is then advanced by the means presently described 75 the tip of the finger bends the wire up and over the pin 147 until the short end lies close to the portion of the wire that is still lying in the arms of the transerrer. (See Figs. 80 12, 15, and 16.) To effect these movements of the lever 149 and finger 155, we employ a sleeve 159, movable on the shaft 135 and provided with an annular groove 160, which receives the arms of a yoke 161, attached to a 85 slide-bar 162. This slide-bar is fitted to a groove in the base of the block 136 and has its rear end provided with a roll 163, which enters a cam-groove 164, (see dotted lines in Fig. 1,) formed in one side of a disk 165, carried by shaft 4. The time of operation of 90 this cam-groove is such as to advance the sleeve 159 while the shaft 135 is stationary, as heretofore described.

The sleeve 159 is provided with a project- 95 ing wedge or incline 166 in line with the end of the lever 149 (see Figs. 11, 13, and 14) and with two ears 167, (see Figs. 12, 13, and 14,) which are provided with short slots 168. The inner end of the finger 155 is fitted be- 100 tween the ears 167 and carries a pin 169, which rides in said slots. By this construc- 105 tion when the sleeve 159 begins its advance movement the incline 166 first rides under the end of lever 149 and moves the latter and the pin 147 from the position shown in full lines in Fig. 11 to the position shown by dotted lines in said figure, and then the inner ends of the slots 168 come in contact with the pin 169 of the finger 155 and advance the 110 latter from the position shown by full lines in Fig. 12 to the position shown by dotted lines in said figure and bending the wire over the pin 147.

Referring now to Figs. 1 and 2, it will be 115 seen that the side of the block 108 is formed as a fixed jaw 170, with which a movable jaw 171 co-operates, the latter being carried by a lever 172, pivoted to the bed-plate 1 at 173 and having its other end provided with a roll 120 174, which is acted upon by a cam 175 on the side of the disk 165, a spring 176 being em- 125 ployed to keep the roll in engagement with the said cam. The timing of the operation of this cam 175 is such as to cause the jaw 171 to move toward the jaw 170 and grip the doubled wire at about the point indicated at 130 y in Fig. 16 just after the finger 155 has ceased to operate. Immediately after this gripping action takes place the straight por- 130 tion of the cam-groove 144 has left the roll 143 and the inclined portion of said groove acts on the roll to move the rack 142 and, through the gearing before described, the

shaft 135 is rotated and the wire is twisted, as indicated in Fig. 17, leaving a loop or eye at the end of the finished tie.

In order to hold the shaft 135 in exact position, with the recess 145 in a vertical plane to permit the wire to be carried into said recess by the transerrer and to permit the finished tie to be carried down and out of said recess by the transerrer at its next quarter-revolution, we affix to the shaft 135 a collar 177, having a flat side 178. A plate 179 (see Figs. 1 and 2) is secured at one end on the cap-piece 137 and has a slot to receive a guide-pin 180, rising from said cap-piece. The free end of the plate 179 is formed as a block 181, overhanging the end of the cap-piece and resting on the collar 177. A flat spring 182 is secured at one end 183 and bears at its other end on the plate 179. The collar 177 is so secured to the shaft 135 that when its flat side 178 is under the block 181 and the shaft 135 is not being positively rotated in either direction the recess 145 is securely held in the plane described. After the rotation of the twister-shaft in one direction to complete the eye of the tie it dwells or remains non-rotary while the eye-forming pin 147 and the bending-finger are withdrawn and immediately thereafter the transerrer-arms begin to rotate another quarter-revolution to bring another blank to the bending and twisting mechanism, while the rack 142 moves in the return direction to reverse the shaft 135 to prepare it for receiving the next blank. At the end of this return movement of the rack its roll 143 is in the other straight portion of the cam-groove 144 and the shaft 135 is held in proper position by the block 181 bearing on the flat side of the collar 177.

The collar 177 is flattened for only a portion of its length, as shown in Fig. 12. When the block 181 rests upon the flat side 178, it acts as a hook or stop to prevent forward motion of the shaft 135 while the sleeve 159 is being moved forward to double the wire by means of the pin 147 and the finger 155. As the twister-shaft 135 makes its first revolution the block 181 rides onto the unflattened portion, the shaft having sufficient longitudinal play to permit this, and the twisting of the wire loop draws the shaft 135, and hence the collar 177, forward, so that by the end of one revolution and until the shaft is returned to its first position after a bale-tie is finished the block 181 rides upon the full round part of the collar 177 and allows free end movement of the shaft 135 as the twisting of the loop progresses. The forward movement of the shaft is limited by a yoke-piece 138, (see Figs. 1 and 2,) adjustably secured to the rear end of the cap 137 by the screw 183, passing through a slot 138' in said yoke-piece, the said yoke-piece straddling the shaft and serving as a stop against which the pinion 138, secured to the shaft, may abut. This contact of the pinion with the stop or yoke-piece occurs just before the shaft 135 has fin-

ished its revolution, thus enabling a tight twist to be given.

The finished tie is held in the openings or recesses of the arms 123 by the hooks 125 until the ends of the levers 126 contact with the stops or lugs 132, (see Fig. 28,) it being understood that there is one of said stops or lugs for each set of arms 123. This contact opens the hooks or latches which hold the finished tie and permits the latter to drop into a final receiver or rack composed of arms 184, which are suitably connected with portions of the frame or standards.

The means for audibly indicating when a predetermined number of finished ties have been deposited in the rack are as follows: A star-wheel 185 (see Figs. 28, 29, 30, and 31) is carried by a shaft 186, mounted in a bearing 187, supported by or formed in one of the standards—in this instance standard 70. Each of the arms 123 of the adjacent set is provided with a projecting lug or pin 188, which is adapted to engage one of the teeth 90 of the star-wheel and partially rotate it as each arm 123 passes said star-wheel. The other end of the shaft 186 carries a worm 189, meshing with a worm-wheel 190, mounted to rotate on a stud 191, which is attached to and supported by a suitable arm or bracket of the standard 70, said arm being indicated in section in Fig. 30 at 192. The stud 191 carries a fixed disk 193, from which a pin 194 projects, and mounted on the stud is a sleeve 195, a bell 196 being mounted on the outer end of the stud. Projecting from the sleeve is an arm 197, having a pin 198, and a spring 199 is coiled about the sleeve and has its ends bearing against the pins 194 and 198, with a tendency to keep the sleeve 195 and arm 197 in the position shown in Fig. 31. Another arm 200 projects from the sleeve and supports the spring-shank 201 of a bell-hammer 202. Pivoted to the disk 193 at 203 is a lever 204, having its longer end 205 provided with a tip or toe 206, adapted to bear on the lower side of the arm 200, and the other end 207 adapted to abut against the other side of the sleeve to limit the outward movement of the longer end 205 of the lever, it being understood that the tendency of spring 199 to hold the parts in the position shown in Fig. 31 causes the arm 200 to press the toe 206 of the lever outward.

Projecting from the side of the worm-wheel 190 are pins 208, there being five of such pins in the form of construction shown in Fig. 31, which pins successively operate to cause the hammer to strike the bell in the manner presently described.

The operation of this portion of the mechanism is as follows: Each quarter-revolution of the transerrer discharges a finished tie and also partially rotates the star-wheel 185. This causes a slight rotation of the worm-wheel, and one of the pins 208 moves a short distance along the cam-shaped outer surface of the longer arm 205 of the lever, and the

successive operations of the star-wheel finally advance said pin along the lever and gradually carry the arm 200 upward and move the sleeve 195 against the tension of spring 199. When the pin 208 that has been so operating along the lever reaches the shoulder 209 thereof, the lever is released, since the edge of the lever, from the shoulder 209 to the tip 206, is concentric with the center of the pivot 203 of said lever. The lever being thus released, the sleeve 195 and the arm 207 are thrown suddenly back by the spring 199 to the position shown in Fig. 31, and this sudden movement throws the striker 202 against the bell, the position of which is indicated by the dotted circle in Fig. 31.

The operations of the different parts of the machine having been mentioned in connection with the detailed description of the mechanisms, the operation of the machine as a whole, if not already apparent, will be made clear by the following general description: The wire from which the ties are made is drawn from a coil or other source of supply (not shown) through the straightener 48, if it is found necessary to so treat the wire, and it then passes to the disks 30, which have an intermittent rotation in the direction of the arrows in Fig. 2, the extent of this feeding movement being adjusted according to the length desired for the completed ties. The wire is pushed by the disks through the guide 51 and through the passage-way in the temporary holder or receiver 74 75 and through the openings in the arms 123 of the rotary transerrer. When the proper length has been so fed, the disks cease to rotate and the cutter 57 severs the wire at the rear end of the guide. Then the temporary holder opens and the shaft 97 of the transerrer makes one-fourth of a rotation and brings other arms 123 into position to receive a severed blank and the first one is moved to carry the just-severed end into the recess 145 of the twister-shaft 135. The pin 147 is next moved across the recess 145, and the bending-finger 155 carries the short end of the wire around the pin 145, after which the jaw 171 clamps the doubled portions of the wire and the shaft 135 rotates to twist the doubled portions of wire between the pin 147 and the holding-jaws. The looped and twisted end of the wire is then released both by the holding-jaws and by the pin 147, and the shaft 97 of the transerrer makes another one-fourth of a rotation, so that the arms thereof bring the second blank to the twister and carry the completed tie down to be discharged into rack 184 for holding a number of the completed ties. Each intermittent movement of the transerrer partially operates the gearing, which finally causes the hammer 202 to strike the bell 196 and indicate that the predetermined number of ties have been deposited in the rack.

Having now described our invention, we claim—

1. A machine for making bale-ties comprising in its construction a cutter and means for feeding varying lengths of wire thereto, 70 means for bending one end of the wire to form a loop, and means for twisting the wire adjacent to the bend formed therein.

2. A machine for making bale-ties comprising in its construction a cutter and means for feeding varying lengths of wire thereto, 75 bending and twisting mechanism, and a rotary carrier for transferring the blanks from the cutter to the said bending and twisting mechanism. 80

3. A machine for making bale-ties comprising in its construction a wire-straightener, a cutter for severing the wire into blanks, adjustable feeding mechanism for drawing the wire through the straightener and feeding 85 varying lengths of it to the cutter, and means for bending over one end of the blank and twisting it.

4. A machine for making bale-ties comprising in its construction an adjustable feeder 90 for the wire, a cutter for dividing the wire into lengths, a holder for the length while being cut, a carrier for taking the length out of said holder, and means for bending and twisting one end of the length to form an eye. 95

5. A machine for making bale-ties comprising in its construction an adjustable feeder for the wire, a cutter for dividing the wire into lengths, a holder for the length while being cut, a carrier for taking the length out of 100 said holder, a bender for doubling one end of the length back upon itself, jaws for clamping the doubled wire, and means for twisting the doubled wire beyond said jaws.

6. A machine for making bale-ties comprising in its construction an adjustable feeder for the wire, a cutter for dividing it into lengths, an intermittently-rotating carrier for taking the lengths after they are cut, a bender and twister for forming an eye in each length 110 while it is retained by the carrier, and a rack for receiving the ties from said carrier. 105

7. A machine for making bale-ties comprising in its construction a feeder for the wire, a cutter for dividing it into lengths, an intermittently-rotating carrier for taking the lengths after they are cut, a bender and twister for forming an eye in each length 115 while it is retained by the carrier, a rack for receiving the ties from the carrier, a bell, and connections between the bell-striker and the carrier for automatically indicating the finishing of a predetermined number of ties. 120

8. A machine for making bale-ties comprising in its construction a shaft having a recess 125 at one end adapted to receive the end of a wire blank, a pin crossing said recess, and a finger movable in a curved path lengthwise of said recess to bend the wire around the pin. 130

9. A machine for making bale-ties comprising in its construction a shaft having a recess at one end adapted to receive the end of a wire blank, a pin movable across said recess,

and a finger movable in a curved path lengthwise of said recess to bend the wire around the pin.

10. A machine for making bale-ties comprising in its construction a shaft having a recess at one end adapted to receive the end of a wire blank, a pin movable across said recess, and a finger having a curved tip with grooved edges and movable in a curved path lengthwise of said recess to carry the tip around the pin to bend the wire into a loop.

11. A machine for making bale-ties comprising in its construction a shaft having a recess at one end adapted to receive the end of a wire blank, a pin movable across said recess, and a finger movable in a curved path lengthwise of said recess to bend the wire around the pin, the said shaft being provided with means for rotating it to twist the doubled portions of the wire.

12. A machine for making bale-ties comprising in its construction a shaft having a recess at one end and provided with means for reciprocally rotating it, means for doubling the end of a wire blank in said recess, a finger movable in a curved path lengthwise of said recess and jaws for holding the doubled portions of the wire during rotation of the shaft in one direction.

13. A machine for making bale-ties comprising in its construction a shaft having a recess at one end and provided with means for reciprocally rotating it, a pin movable across the recess, a bending-finger movable in a curved path lengthwise of said recess for doubling the end of the wire over the pin, and jaws for holding the doubled portions of the wire during rotation of the shaft in one direction.

14. A machine for making bale-ties comprising in its construction a shaft having a divided end to form a recess and provided with means for reciprocally rotating it, detent mechanism for accurately holding the shaft during the dwell at each end of its rotations, a carrier for placing the end of a blank in said recess, and a finger movable in a curved path lengthwise of said recess for bending the wire into a loop in said recess.

15. A machine for making bale-ties comprising in its construction a shaft having a divided end to form a recess and provided with means for reciprocally rotating it, detent mechanism for accurately holding the shaft during the dwell at each end of its rotations, a carrier for placing the end of a blank in said recess while the shaft is held by the detent, a pin movable across said recess, a bending-finger for doubling the wire into a

loop around the pin, and jaws for clamping the doubled portions of the wire during the rotation of the shaft to twist said doubled portions, the said detent mechanism holding the shaft stationary while the carrier removes the twisted loop from said recess.

16. A machine for making bale-ties comprising in its construction a pair of feed-disks

adapted to grasp and feed the wire between their peripheries, means for intermittently rotating them, said means comprising adjustable mechanism for varying the amount of feed, a cutter, and means for forming a twisted loop in one end of each length of wire cut off.

17. A machine for making bale-ties comprising in its construction a pair of feed-disks having grooved peripheries adapted to grasp the wire between them, means for intermittently rotating them, friction devices for preventing their backward rotation, and means for cutting the wire into lengths and forming a twisted loop in the end of each length.

18. A machine for making bale-ties comprising in its construction a pair of feed-disks each having a pawl, ratchets engaging said pawls, multiplying-gearing for rotating the ratchets, and a reciprocating rack for operating said gearing.

19. A machine for making bale-ties comprising in its construction a pair of feed-disks each having a pawl, ratchets engaging said pawls, multiplying-gearing for rotating the ratchets, a slide-rack for operating the gearing, a slotted lever having a rod connecting it with the rack, a continuously-rotated disk, and a wrist-pin carried by said disk and operating in the slot of the lever.

20. A machine for making bale-ties comprising in its construction a pair of feed-disks each having a pawl, ratchets engaging said pawls, multiplying-gearing for rotating the ratchets, a slide-rack for operating the gearing, a slotted lever having a rod connecting it with the rack, a continuously-rotated disk, having a diametrical groove, and a wrist-pin adjustable along said groove and operating in the slot of the lever.

21. A machine for making bale-ties comprising in its construction a pair of disks adapted to feed the wire between their peripheries and having extended hubs, friction-pads bearing on said hubs, a yoke or strap embracing both of said pads, and means for rotating the disks simultaneously but intermittently in opposite directions.

22. A machine for making bale-ties comprising in its construction means for intermittently feeding the wire, said means including mechanism for varying the length of feed, a cutter for severing the wire into blanks, a receiver for temporarily holding the blanks, and mechanism for removing the blanks from the said receiver.

23. A machine for making bale-ties comprising in its construction means for intermittently feeding the wire, said means including mechanism for varying the length of feed, a cutter for severing the wire into blanks, a receiver for temporarily holding the blanks, said receiver consisting of two separable portions between which the blank is fed, and mechanism for opening said portions and removing the blanks.

24. A machine for making bale-ties comprising in its construction means for inter-

mittently feeding the wire, a cutter for severing it into blanks of a given length, a receiver for temporarily holding the blanks, said receiver consisting of separated sections each of which is composed of two separable portions to receive the blank between them, means for raising the upper portions, and carrier-arms adapted to pass between the sections to remove the blanks.

10 25. A machine for making bale-ties comprising in its construction feeding and cutting mechanism, a temporary receiver for the lengths of wire or blanks, and a rotary carrier consisting of a shaft having a plurality of sets of arms, each of said arms having an open slot and a spring-pressed hook or latch whereby the blanks are retained in the slots until the latches are caused to open the slots.

20 26. A machine for making bale-ties comprising in its construction feeding and cutting mechanism, a temporary receiver for the lengths of wire or blanks, a rotary carrier consisting of a shaft having a plurality of sets of arms, each of said arms having an open slot and a spring-pressed hook or latch whereby the blanks are retained in the slots until the latches are caused to open the slots, and a stop arranged in the path of movement 30 of portions of the latches to automatically open them.

27. A machine for making bale-ties comprising in its construction adjustable feeding and cutting mechanism for forming wire blanks of different lengths as desired, a shaft having a plurality of sets of arms provided with means for admitting and releasing the blanks one at a time, means for rotating the shaft and arms step by step, and means for 40 bending and twisting one end of each blank while retained by the arms.

28. A machine for making bale-ties comprising in its construction adjustable feeding and cutting mechanism for forming wire blanks of different lengths as desired, a shaft having a plurality of sets of arms provided with means for admitting and releasing the blanks one at a time, means for rotating the shaft and arms step by step, means for bending and twisting one end of each blank while retained by the arms, and means for automatically discharging each length of wire after it has been formed into a tie by the bending and twisting mechanism.

55 29. A machine for making bale-ties comprising in its construction adjustable feeding and cutting mechanism, a shaft for bending and twisting one end of a blank and located out of the line of feed, and a transerrer 60 for carrying a blank laterally to the bending and twisting mechanism.

30. A machine for making bale-ties comprising in its construction adjustable feeding and cutting mechanism, a shaft for bending and twisting one end of a blank and located out of the line of feed, and a transerrer for carrying a blank laterally to the bending and

twisting mechanism, and from said mechanism to a receiving-rack.

31. A machine for making bale-ties comprising in its construction feeding and cutting mechanism, a shaft for bending and twisting one end of a blank, and located out of the line of feed, and a transerrer for carrying a blank laterally to the bending and twisting mechanism, and from said mechanism to a receiving-rack, a bell, and connections operated by the movements of the transerrer to ring the bell when a predetermined number of ties have been deposited in said rack. 70 80

32. In a machine of the character specified, the combination with the bracket 15 of the shafts 3 and 4 geared together at one end and the latter having the gear 11 at the other end, the short shaft 13 mounted in said bracket 85 and having the gear 12 and grooved disk 17, the wrist-pin 24 adjustable along the groove of the disk, the lever 27 having a slot for said wrist-pin, and feed-disks operated by said lever. 90

33. In a machine of the character specified, the combination with the bracket 15 of the shafts 3 and 4 geared together at one end and the latter having the gear 11 at the other end, the short shaft 13 mounted in said bracket 95 and having the gear 12 and grooved disk 17, the wrist-pin 24 adjustable along the groove of the disk, the lever 27 having a slot for said wrist-pin, the slide 33 having two racks and connected with the lever by a rod, feed-disks 30, and multiplying-gearing between said racks and disks, said gearing including ratchet or clutch mechanism to drive the disks in but one direction. 100

34. In a machine of the character specified, 105 the combination with the feeding-disks 30 having means for preventing backward rotation and having pawls 39, of the shafts 35 having pinions 36 and ratchets 37, the compound pinions 47, the slide 33 having rack-teeth, and 110 means for reciprocating said rack.

35. In a machine of the character specified, the combination with the feeding-disks 30 having hubs 40 provided with friction-surfaces, of means for rotating said disks intermittently, the pads 41 fitted to said hubs 40, the yoke or strap 42 having threaded ends, the cap 43 through which said threaded ends are passed, and the nuts 44 on said threaded ends. 115 120

36. In a machine of the character specified, the combination with the standard 31 having offsets 32, of the rack 33 fitted to slide in said offsets and having means for reciprocating it, the tubular shafts 35 having bearings in 125 said standard and provided with pinions 36 and ratchets 37, the shafts 38 fitted in the tubular shafts, the disks 30 on said shafts 38 and having pawls 39, and means for preventing backward rotation of the disks. 130

37. In a machine of the character specified, the combination with the standard 31 having offsets 32, of the rack 33 fitted to slide in said offsets and having means for reciprocating it,

the tubular shafts 35 having bearings in said standard and provided with pinions 36 and ratchets 37, the shafts 38 fitted in the tubular shafts, the disks 30 on said shafts 38 and having pawls 39 and hubs 40, the friction-pads 41 bearing on said hubs, and the strap 42 and cap 43 inclosing the pads.

38. In a machine of the character specified, the combination with the feed - disks and 10 means for operating them, of the guide 51 for receiving the wire from the disks and having a rounded rear or exit end, and the cutter 57 movable across said rounded end to coöperate therewith in severing the wire, the guide being provided with means for adjusting its longitudinal position, and the cutter being provided with means for adjusting its normal position relatively to the guide.

39. In a machine of the character specified, 20 the combination with the feed-disks, of the standard 31 supporting said disks and having the recess 65, the guide 51, the cutter 57, and the lever 64 for operating the cutter, said lever extending through and being fulcrumed 25 in said recess 65.

40. In a machine of the character specified, the combination with the feed-disks, of the plate 53 adjustably mounted on a portion of the frame and having the ear 52, the guide 30 51 adjustably secured in said ear, the slide 58 fitted to a groove or way in the plate 53, the cutter 57 adjustably secured to said slide, and means for reciprocating the slide.

41. In a machine of the character specified, 35 the combination with the feed-disks, of the plate 53 adjustably mounted on a portion of the frame and having the ear 52, the guide 51 adjustably secured in said ear, the slide 58 fitted to a groove or way in the plate 53, and 40 having shoulder 63 and offset 62, the spring 61 between said offset and a portion of the plate 53, the cutter 57 adjustably secured to the slide, the lever 64 having one end bearing against the shoulder 63, and a cam for 45 operating against the other end of the lever.

42. In a machine of the character specified, the combination with feeding and cutting mechanism, of the temporary receiver consisting of the elongated table 74 and the cover 50 75 hinged thereto and having a wire-receiving groove 76, and means for raising the cover and for removing the wire.

43. In a machine of the character specified, the combination with feeding and cutting 55 mechanism, of the temporary receiver consisting of the elongated table 74 and hinged cover 75 provided with a wire - receiving groove, said table and cover being made in separated sections, means for raising the 60 cover, and devices for removing the wire, said devices being movable through the space between the sections.

44. In a machine of the character specified, the combination with feeding and cutting 65 mechanism, of the temporary receiver consisting of the elongated table 74 and the cover 75 hinged thereto and having a wire-receiving

groove 76, and the arm 78, the elbow-lever 79 adapted to depress the arm 78 to raise the cover, and means for oscillating said lever 79.

45. In a machine of the character specified, the combination with the table 74 and hinged cover 75 having groove 76 and arm 78, of the elbow-levers 79 and 82 having connecting- 75 link 81, one arm of the lever 79 resting on the arm 78 of the cover, the rock-shaft 86 having arms 85 and 88, the link 84 connecting the arm 85 with lever 82, and means for raising and lowering the arm 88.

46. In a machine of the character specified, the combination with the table 74 and hinged cover 75 having groove 76 and arm 78, of the elbow-levers 79 and 82 having connecting-link 81, one arm of the lever 79 resting on the 85 arm 78 of the cover, the rock-shaft 86 having arms 85 and 88, the link 84 connecting the arm 85 with lever 82, the pin 89 carried by the arm 88, the spring 90, the slide 33, and the pivoted finger 92 carried by said slide and 90 adapted to strike the arm 88 and raise it.

47. In a machine of the character specified, the combination with the table 74 and hinged cover 75 having groove 76 and arm 78, of the elbow-levers 79 and 82 having connecting-link 81, one arm of the lever 79 resting on the arm 78 of the cover, the rock-shaft 86 having arms 85 and 88, the link 84 connecting the arm 85 with lever 82, the pin 89 carried by the arm 88, the spring 90, the slide 33, the 100 finger 92 pivoted to the slide, a back stop or pin 95 carried by the slide, and a spring 96 adapted to normally hold the pivoted finger against the pin 95 with the upper end of said finger projecting above the plane of the normal position of the end of arm 88.

48. In a machine of the character specified, the combination with the standards 70 and 71, of the rod 72 supported thereby, the hangers 73 carried by the rod, the table 74 in separated 110 sections supported by the hangers, the cover 75 hinged to the table and also in separated sections, the connecting-strip or bridge connecting the sections of the cover, and means for raising the cover.

49. In a machine of the character specified, the combination with the shaft 97 having a plurality of sets of arms 123 and mounted in suitable bearings, means for adjusting said bearings, devices for retaining wire blanks in 120 said arms, and means for feeding the blanks thereto.

50. In a machine of the character specified, the combination with the shaft 97 having arms 123, and the disk 103 provided with 125 notches 104, of the lever 113 having pawl 115, the lever 116 and means for operating it, link 121 connecting the levers 113 and 116, and means for locking the disk and shaft.

51. In a machine of the character specified, 130 the combination with the shaft 97 having arms 123, and the disk 103 provided with notches 104, of the lever 113 having pawl 115, the lever 116 and means for operating it, link

121 connecting the levers 113 and 116, and made in two parts adjustably joined at 122, and means for locking the disk and shaft.

52. In a machine of the character specified, the combination with the shaft 97 having arms 123, and the disk 103 provided with notches 104 and 106, of the lever 113 having the cam 114 and pawl 115, the spring-bolt 107 adapted to enter the notches 106 and having the pin 112 adapted to be engaged by the cam 114, and means for oscillating the lever 113.

53. In a machine of the character specified, the combination with the shaft 97 having means for intermittently rotating it, of the plurality of sets of arms 123 carried by said shaft, each of said arms having an open slot 124 in its end, and the latch or hook 125 carried by the lever 126 pivoted to said arm and having a spring for normally holding the hook 125 across the slot 124.

54. In a machine of the character specified, the combination with the shaft 97 having means for intermittently rotating it, of the plurality of sets of arms 123 carried by said shaft, each of said arms having an open slot 124 in its end, and the latch or hook 125 carried by the lever 126 pivoted to said arm and having a spring for normally holding the hook 125 across the slot 124, the said lever 126 having a projecting pin 128, and a fixed stop or lug 132 carried by a part of the frame of the machine and located in the path of movement of the pins 128 carried by the latch-levers, whereby the hooks will automatically open the slots 124.

55. In a machine of the character specified, the combination with the shaft 135 having means for bending the end of a piece of wire and having the pinion 138, of the rack 142, the short shaft having the gear 139 and pinion 141 meshing respectively with the pinion 138 of the shaft and with the said rack 142, and means for reciprocating the rack.

56. In a machine of the character specified, the combination with the shaft 135 having means for bending the end of a piece of wire and having the pinion 138, of the rack 142, the short shaft having the gear 139 and pinion 141 meshing respectively with the pinion 138 of the shaft and with the said rack 142, the roll 143 carried by said rack, and the rotary cylinder 69 having cam-groove 144 receiving the roll, said cam-groove being formed with two straight portions to permit the rack to dwell at each end of its reciprocations.

57. In a machine of the character specified, the combination with the shaft 135 having means for reciprocally rotating it and having the wire-receiving recess 145, of the pin 147 movable across said recess and having a beveled end, the bending-finger 155 movable in a plane at a right angle to the axis of the pin, and means for reciprocating said finger.

58. In a machine of the character specified, the combination with the shaft 135 having means for reciprocally rotating it and having the wire-receiving recess 145, of the pin 147

movable across said recess, the lever 149 connected with the pin, a spring for moving the lever in one direction, a wedge or incline for moving it in the other direction, the pin 154 across the lower side of the recess, and the slotted finger 155 guided on said pin 154 and having means for reciprocating it in the recess.

59. In a machine of the character specified, the combination with the shaft 135 having the recess 145, of the movable eye-forming pin 147, the pin 154 across the lower side of the recess, the finger 155 having the curved tip 156 grooved along its edges and having the curved slot 158 through which the pin 154 passes, and means for reciprocating the finger.

60. In a machine of the character specified, the combination with the shaft 135 having the recess 145, of the movable eye-forming pin 147, the pin 154 across the lower side of the recess, the finger 155 having the curved tip 156 grooved along its edges and having the curved slot 158 through which the pin 154 passes, the pin 169 carried by the rear end of the finger 155, the collar 159 movable along the shaft and having the slotted ears 167 receiving said pin 169, and means for moving the collar along the shaft.

61. In a machine of the character specified, the combination with the shaft 135 having means for reciprocally rotating it and having the wire-receiving recess 145, of the pin 147 movable across said recess, the pin-operating lever 149, the spring 152, the pin 154 across the lower side of the recess, the finger 155 having curved tip 156 and curved slot 158 and pin 169, the sleeve 159 having the wedge or incline 166 and the ears 167 provided with slots to receive the pin 169, and means for moving the sleeve along the shaft.

62. In a machine of the character specified, the combination with the shaft 135 having means for reciprocally rotating it and having the wire-receiving recess 145, of the pin 147 movable across said recess, the finger 155 adapted to bend the wire around the pin 147, the collar 177 on the shaft and having the flat side 178, and a spring-pressed block 181 bearing on said collar.

63. In a machine of the character specified, the combination with the shaft 135 having means for reciprocally rotating it and for engaging and doubling a wire, of the collar 177 on said shaft having a flat side 178, a spring-pressed block riding on said collar, and the stop or yoke piece 138.

64. In a machine of the character specified, the combination with the twister-shaft 135 having the recess 145 and pin 147 and the bending-finger 155 movable in a curved path lengthwise of said recess, of the fixed jaw 170, the lever 172 having the jaw 171, and means for closing the jaws while the shaft is rotated.

65. In a machine of the character specified, the combination with the transerrer-arms having pins 188, of the star-wheel 185 adapted to be successively engaged by said pins, the

shaft 186 carrying the star-wheel and having the worm 189, the worm-wheel 190 having pins 208, a bell, and a bell-hammer operated through the medium of said pins.

- 5 66. In a machine of the character specified, the combination with the shaft 186 having a star-wheel and a worm, the stud 191 having disk 193, the worm-wheel having pins 208 and mounted on the stud, the lever 204 pivoted to 10 the disk 193 and having a cam-surface in the path of movement of the pins 208, a bell, a bell-hammer adapted to be operated by movements of the lever 204, and means for rotating the star-wheel.
- 15 67. In a machine of the character specified, the combination with the shaft 186 having a star-wheel and a worm, the stud 191 having

disk 193, the worm-wheel having pins 208 and mounted on the stud, the lever 204 pivoted to the disk 193 and having a cam-surface in the 20 path of movement of the pins 208, the sleeve 195 mounted on the stud and having arms 197 and 200, the latter arm carrying a bell-hammer and located in the path of movement of one end of the lever 204, a spring connected 25 with the arm 197, a bell, and means for rotating the star-wheel.

In testimony whereof we affix our signatures in presence of two witnesses.

FRANK B. MANVILLE.
CHARLES S. WEEKS.
